Patented June 9, 1925.

UNITED STATES PATENT OFFICE.

JAMES F. CONNOR, OF CLEVELAND, OHIO.

CUFF LINK.

Application filed October 25, 1924, Serial No. 745,907.

To all whom it may concern:

Be it known that I, JAMES F. CONNOR, a citizen of the United States, residing at Cleveland, in the county of Cuyahoga and 5 State of Ohio, have invented certain new and useful Improvements in Cuff Links, of which the following is a specification, reference being had to the accompanying drawings.

10 This invention relates to an improved cuff link of the type shown in my Patent #1,512,877, granted on the 21st day of October, 1924.

In this cuff link a pair of normally abutting studs were provided, one corresponding to each of the buttonholes of a cuff, these studs being connected by a cord passing around a spring-actuated drum in one of the studs, this resiliently wound cord 20 urging the two studs together and into abutting relation but permitting the studs to be separated when it was desirable to turn up the cuff or pull up the sleeve of the shirt.

25 The object of the present invention is to provide certain improvements upon the cuff link or button shown in my patent whereby to render the same of simpler construction and easier to manufacture, and to provide 30 for an easier threading of the cord and guiding of the cord from the spring-actuated drum through one of the studs and into engagement with the other stud, and in this connection to provide such a guide as 35 will prevent the cord from wearing out as rapidly as it otherwise would do.

A further object is to do away with the hollow shaft or barrel arbor which is disclosed in my patent, thus permitting the 40 cord to run more directly and freely.

A still further object is to so form one of the heads or buttons of the link that the shaft upon which the spring-actuated winding drum turns is supported without the 45 necessity of using the arbor shown in my prior patent and at the same time provision is made for a freer movement of the cord.

Another object is to so construct the opposite head, stud or button that a knot may 50 be readily tied in the cord to connect the cord to this stud or button.

Other objects will appear in the course of the following description.

55 My invention is illustrated in the accompanying drawing, wherein:—

Figure 1 is a vertical sectional view of a

cuff button constructed in accordance with my invention;

Figure 2 is a section on the line 2—2 of 60 Figure 1;

Figure 3 is a section on the line 3—3 of Figure 1;

Figure 4 is a fragmentary perspective view of the head end of the stud 10;

Figure 5 is an end elevation of the two 65 studs;

Referring to these drawings, 10 designates one stud, button or head and 11 the opposite stud, button or head. The head 10 at its outer end is formed cylindrical, as 70 at 12, to constitute a cylindrical casing for a coiled spring 13. The inner end of this spring is connected by any suitable means to an arbor 14 mounted in the member 10, the outer end of this spring being connected 75 to a spring drum 15.

The member 10, as illustrated in Figure 2, is somewhat oblong in cross section or is formed, in other words, with substantially flat faces on two of its sides. The shaft 14 80 extends downward into this relatively narrow oblong portion, as shown in Figure 2, and fits the same snugly, and a lug 16 projects outward from this shaft also fitting this oblong portion which prevents any rotation of this shaft.

The cylindrical portion 12 is, of course, closed by a cover 17 having a marginal flange which fits down over the portion 12. Thus the spring drum 15 is entirely enclosed within the head portion of the stud 10. Wound upon the drum is a cord or 90 other flexible element 18 which passes from the drum downward into and through the neck 19 of the member 10 and through an opening 20 at the inner extremity of this neck 19, the margins of the opening being inwardly turned so as to form a smooth surface. The member 11 is also somewhat oval 95 in cross section at its neck and this neck is engaged with a relatively wide head 21. The neck is hollow and formed with an opening 22 which extends transversely 100 through the neck so that access may be had to the knot 23 on the extremity of the cord 18. Thus it is an easy matter to put the two members 10 and 11 together, thread the cord 18 through the aligned openings 20, and 105 then knot the cord 23.

In order to guide the cord inward and centrally from the spring drum, I form upon the side wall of the head 12 a down-

wardly inclined groove 24 by which the cord is guided downward and toward the beginning of the neck 10, and in order to provide for the ready insertion of the cord 5 in this groove I intersect the ends of the groove 24 by slots 25 which thus very greatly facilitate the insertion of the cord. It will be noted that the necks 11 and 19 are 10 relatively small at their meeting ends so that the necks will pass into conjoined buttonholes so that there will be no large protuberance on each side of the conjoined overlapping thicknesses of cuff, as in my prior patent. This renders it very easy to 15 insert this cuff fastener in place.

Under normal conditions, the links, studs or buttons will be in contacting engagement with each other. When, however, it is desired to draw the sleeves up upon the arms, 20 as when washing or doing any work which is liable to soil the cuffs, the sleeves can be simply drawn upward and as they move upward on the arms the studs or links are drawn apart and the cord 18 drawn out of 25 the member 10. As it is drawn out it will be unwound from the drum against the tension of the spring 13. This spring causes the cord to hold tightly and hold the cuff in close engagement about the upper portion 30 of the arm so that the cuff or sleeve will not be liable to slip downward. Of course, as soon as the sleeve is drawn downward to its normal position, the spring drum will draw the two sections toward each other and the 35 link will be in its ordinary position.

I claim:—

1. A cuff button comprising opposed studs, one of the studs being hollow and having a head at one end disposed in a plane at right 40 angles to the axis of the stud, a spring-retracted drum rotatably mounted in the said hollow head and rotating concentrically to the axis of the stud, and a flexible element wound upon said drum and carried through 45 the hollow stud and connected to the other stud, both of said studs toward their meeting ends being contracted to form relatively narrow abutting necks.

2. A cuff button comprising opposed studs, 50 both of the studs being hollow, a spring-retracted drum rotatably mounted in one stud, a flexible element wound upon said drum and carried through the hollow stud and into the other hollow stud and fastened 55 therein, both of said studs toward their meeting ends being contracted to form relatively narrow abutting necks, the second named stud having an aperture extending through it whereby the extremity of the 60 flexible element may be knotted.

3. A cuff link comprising two hollow 65 studs, each stud consisting of a head and a neck, the ends of the necks abutting and each neck having walls curving centrally and longitudinally from the head, a spring-actuated

drum in one head, and a flexible element carried by the drum extending through one of the necks and guided by the curved inside face thereof and extending into the other neck and fastened within said last named 70 neck.

4. A cuff link comprising two hollow studs, each stud consisting of a head and a neck, the ends of the necks abutting and each neck having walls curving centrally and longitudinally from the head, a spring-actuated drum in one head, and a flexible element carried by the drum extending through 75 one of the necks and guided by the curved inside face thereof and extending into the other neck and fastened within said last named neck, the last named stud having an aperture extending through its side walls whereby the cord may be knotted.

5. A cuff link comprising two hollow 85 studs, each consisting of a head and a neck, each neck being approximately rectangular in cross section, two side walls of the neck being curved centrally and longitudinally and the ends of the necks abutting, a shaft 90 mounted in the neck of one stud and extending into the head thereof, the shaft being held from rotation by the walls of the neck, a spring-actuated drum mounted upon the walls of the shaft, a flexible element attached to said drum and extending through 95 the corresponding neck and into the neck of the other stud and fastened therein, the cord being guided by the curved inner face of the first named neck, the second named stud having an aperture extending through 100 its side walls whereby the cord may be fastened.

6. A cuff link comprising two hollow 105 studs, each stud consisting of a head and a neck, the neck of each stud being approximately rectangular in cross section and being relatively narrow in one dimension, the end walls of the neck being centrally and longitudinally curved to the end of the stud, the ends of the stud abutting against each other and having aligned apertures, a shaft 110 mounted in one of said studs and held from rotation by the side walls thereof, a spring-actuated drum mounted upon the shaft, a flexible element carried by the drum passing 115 downward into the corresponding neck and guided by a curved wall thereof and passing through the apertures in the ends of the stud and fastened within the other stud, and a guide formed upon the head of the first named stud for guiding said flexible element from the drum into the neck of the stud.

7. A cuff link comprising two hollow 125 studs, each stud consisting of a head and a neck, the neck of each stud being approximately rectangular in cross section and being relatively narrow in one dimension, the end walls of the neck being centrally and longitudinally from the head, a spring-actuated

tudinally curved to the end of the stud, the ends of the stud abutting against each other and having aligned apertures, a shaft mounted in one of said studs and held from 5 rotation by the side walls thereof, a spring-actuated drum mounted upon the shaft, a flexible element carried by the drum passing downward into the corresponding neck and guided by a curved wall thereof and passing 10 through the apertures in the ends of the stud and fastened within the other stud, and a guide formed upon the head of the first named stud for guiding said flexible element from the drum into the neck of the 15 stud, the second named stud having an aperture through its side walls whereby the flexible element may be fastened.

8. A cuff link comprising two hollow studs, each stud consisting of a head and a 20 neck, the neck of each stud being approximately rectangular in cross section and being relatively narrow in one dimension, the end walls of the neck being centrally and longitudinally curved to the end of the stud, 25 the ends of the stud abutting against each other and having aligned apertures, a shaft mounted in one of said studs and held from rotation by the side walls thereof, a spring-actuated drum mounted upon the shaft, a

flexible element carried by the drum passing 30 downward into the corresponding neck and guided by a curved wall thereof and passing through the apertures in the ends of the stud and fastened within the other stud, and a downwardly inclined guide groove formed 35 upon the inner face of the head whereby to guide the flexible element from the drum to the hollow neck of the stud, and vertical slots in the wall of the head intersecting the ends of the guide groove.

9. A cuff button comprising opposed studs, one of the studs being hollow, both of said studs toward their meeting ends being contracted to form relatively narrow abutting necks, a spring-retracted drum rotatably mounted in the hollow stud, and a flexible element rotatably mounted upon said element and carried through the neck of the hollow stud, the neck of the other stud having an aperture in its neck through which the flexible element extends and the second named stud having an aperture extending transversely through it whereby the extremity of the flexible element may be fastened.

In testimony whereof I hereunto affix my- 55 signature.

JAMES F. CONNOR.
